G. C. RICKARBY

ADVERTISING DEVICE

Filed Feb. 14, 1923

UNITED STATES PATENT OFFICE.

GUSTAVE C. RICKARBY, OF RICHMOND HILL, NEW YORK.

ADVERTISING DEVICE.

Application filed February 14, 1923. Serial No. 618,886.

To all whom it may concern:

Be it known that I, GUSTAVE C. RICKARBY, residing at 10441 90th Avenue, Richmond Hill, in the county of Queens, city and State 5 of New York, and being a citizen of the United States, have invented a new and useful Improvement in Advertising Devices, of which the following is a specification.

This invention relates to new and useful 10 improvements in advertising devices and has for its principal object to provide a device for the display of advertising cards, posters and the like in combination with news pictorials.

15 Another object of the invention resides in the provision of a device which may be illuminated so that its utility is materially enhanced as its functions may be performed after dark, as well as during daylight hours.

20 A further object of the invention is to provide a display device in which independently and interchangeably supported advertising cards or posters may be retained on display in such a manner as to permit their 25 ready removal and substitution.

As another object, this invention contemplates the provision of light diffusing means 30 for the artificial illuminating devices, so designed as to effectively diffuse the light rays over the display surface and at the same time prevent the rays from striking into the eyes of an observer.

As a further object the invention contemplates the provision of an ornamental 35 housing designed to protect the advertising and news matter from the ravages of the elements and to provide a suitable door so arranged to permit ready access to the advertising and news matter as well as to the 40 interior of the illuminating device containing chambers, so that the illuminating devices may be readily changed and substituted in the event they should become inoperative or disarranged.

45 With the above and other objects in view, which will become more apparent as the description proceeds, the invention consists in the novel construction, combination and arrangement of parts which will be fully set forth in the following specification, claimed 50 and illustrated in the accompanying drawing, in which:—

Figure 1 is a front view in elevation of

this improved display device, showing a portion of the same in section. 55

Figure 2 is a horizontal sectional view taken on line 2—2 of Fig. 1.

Figure 3 is a vertical sectional view taken on line 3—3 of Fig. 1.

Figure 4 is a fragmentary perspective 60 view of one of the spacing strips.

Referring to the drawings by characters of reference, the numeral 10 designates generically a housing which comprises a back wall 11 having secured to opposite ends the 65 vertically extending side walls 12. Secured to the upper and lower edges of the back wall 11 are the top and bottom walls 13 and 14 respectively and attached to the upper side of the top wall 13 is a plate 15, the forward edge of which overhangs the front of the device as at 16 as clearly shown in Figure 3.

Secured at the forward edges of the side and end walls 12, 13 and 14 are strips 17 75 forming pockets or chambers 18, for housing illuminating devices 19, such as electric lamps.

Secured to and extending forwardly from the back wall 11 are vertically extending 80 plates 20 of a suitable light diffusing material such as ground glass, and extending in the same manner from the back wall 11 are horizontally disposed plates 21 of a similar substance. It is to be noted that these plates 85 are spaced inwardly with relation to the side, top and bottom walls so as to form a complete enclosure for the illuminating devices 19, but are likewise spaced inwardly from the inner edges of the strips 17 to provide a space through which access to the 90 chambers 18 may be had when it is desired to adjust or change the illuminating devices.

A door designated generically by the numeral 22 is hingedly supported to one of the 95 vertical strips 17 and is of such size as to wholly close the opening between the inner edges of the said strips. This door comprises a frame formed of the vertical strips 23 and the horizontal strips 24 which are 100 secured together at opposite ends to support a transparent panel 25 of glass or a similar material.

As illustrated in Figures 2 and 3, these strips 23 and 24 are of such width as to 105 provide closeness for the spaces between the

inner edges of the strips 17 and the plates 20 and 21, so as to exclude dust and at the same time prevent the escape of light from the chambers 18. Obviously easy access to the chambers may be had when the door is open.

Secured to the back wall 11 adjacent the inner sides of the plates 20 and 21 are strips 26 which are substantially T-shaped in cross section to provide overhanging flanges for retaining the advertising cards in place.

Similar T-shaped strips 27 are secured to the wall 11 in spaced relation to the strips 26 to provide a central space surrounded by a border of equal width on all sides. As shown in Figures 2 and 3 the inner flanges of the strips 27 are designed to overlie the edges of a panel 28 of a soft substance such as cork or white pine, in order to retain said panel in place.

It is preferable that said panel 28 be covered with a suitable fabric 29 such as burlap, but it is to be understood that such covering may be dispensed with if so desired.

In order to removably secure the advertising cards in proper position, there are provided the dividing strips 30 which are substantially T-shaped in cross section to provide overhanging flanges 31, and formed at opposite ends of said strips in longitudinal alignment with the stem, are oppositely extending tongues 32 which are adapted to be received beneath the adjacent flanges of the strips 26 and 27. Such arrangement will allow the dividing strips to be readily adjusted to fit advertising cards of varying width.

In use, suitable advertising cards are placed in the border and retained beneath the flanges of the stationary and dividing strips and news pictures and similar matter is secured to the panel 28 by means of fastening devices such as push pin or thumb tacks.

Obviously the news matter may be changed as frequently as desired without disturbing the advertising matter. Likewise it is possible to change the advertising matter without necessarily changing the news matter.

Further the illuminating means may be kept in proper repair by gaining access to the chambers 18 through the spaces between the strips 17 and plates 20 and 21.

While in the foregoing there has been shown and described the preferred embodiment of this invention, it is to be understood

that certain minor changes in the details of construction, combination and arrangement of parts may be resorted to without departing from the spirit and scope of the invention as claimed.

What is claimed is:—

1. An advertising device comprising a housing, translucent panels within the housing in spaced relation to the top, bottom and side walls, said walls and panels forming chambers, permanent plates partially overlying the front open sides of the chambers, a transparent door for closing the front of the housing, the door frame being so arranged as to co-operate with the permanent panels in completely closing the chambers, illuminating means within said chambers and means in the rear wall of the housing for supporting advertising and news matter.

2. An advertising device comprising, a housing open at one side, translucent panels arranged in spaced parallel relation to the top, bottom and end walls of the housing to form chambers, permanent strips secured to the housing and partially overlying the front open sides of the chambers, a transparent door for closing the front of the housing, the frame of said door co-operating with the strips in completely closing the open sides of the chambers, strips secured to the front face of the back wall of the housing, spaced parallel strips associated therewith, and adjustable spacing strips extending transversely between the first named strips.

3. An advertising device comprising, a housing open at one side, translucent panels arranged in spaced parallel relation to the top, bottom and end walls of the housing to form chambers, permanent strips secured to the housing and partially overlying the front open sides of the chambers, a transparent door for closing the front of the housing, the frame of said door co-operating with the strips in completely closing the open sides of the chambers, flanged strips secured to the front face of the back wall of the housing, spaced parallel flanged strips associated therewith, and adjustable spacing strips extending transversely between the first named strips, illuminating means in the chambers and tongues on the ends of the adjustable strips for engaging beneath the flanges of the stationary strips whereby said adjustable strips will be removably and adjustably held.

GUSTAVE C. RICKARBY.
